J. Hotchkiss.
Suspenders.

Nº 11160

Patented Jun. 27, 1854.

UNITED STATES PATENT OFFICE.

JULIUS HOTCHKISS, OF WATERBURY, CONNECTICUT.

SUSPENDER-END.

Specification of Letters Patent No. 11,160, dated June 27, 1854.

To all whom it may concern:

Be it known that I, JULIUS HOTCHKISS, of Waterbury, in the county of New Haven and State of Connecticut, have invented a new 5 and useful Improvement in Suspender-Ends; and I do hereby declare that the following is a full and exact description thereof, reference being had to the accompanying drawings and to the letters of reference 10 marked thereon.

The nature of my invention consists in attaching the straps to each end of the buckle by a double connection, whereby a self-adjusting action is obtained that adapts itself 15 to the position of the body.

To enable others skilled in the art to make and use my invention, I will proceed to describe its construction and operation.

In constructing the suspender strap, I take 20 two pieces of narrow web, half inch wide (but may be of different width), and of the length necessary for the strap required; these two pieces of web I place side by side, and with needle and thread neatly and firmly 25 sew the selvage edges together from one of the ends, a sufficient distance to make the union firm and strong; then I leave a space or opening of sufficient length for the button hole or loop required, and then sew the 30 selvage edges of the two pieces of web together again for half an inch or more, thus forming the button hole or loop in one end of the strap, as shown in the accompanying drawing at A, and the buttonhole or loop in 35 the other end of the strap after being attached to the buckle as hereinafter described is formed in the same manner by sewing the other ends of the two pieces of web together as shown in the drawing at B.

40 In constructing the buckle to which my invention is to be applied, I form the bar of the buckle with a flat lip behind the tongues, in each end of which I cut out a strip or opening in length equal to the width of the

web of the straps, and of sufficient width to 45 receive the web of the straps, and allow it to play easily therein as shown in the drawing at C, C.

If preferred, instead of the lip on the bar of the buckle with the openings to receive 50 the straps as above described, the bar of the buckle may be formed in the usual manner with wire loops of the required form attached to the bar of the buckle behind the tongues to receive the straps instead of the 55 lip with the openings as above described.

After the buttonhole or loop is formed in one end of the two pieces of web as shown in the drawing at A, to attach the strap to the buckle I take the left hand strip of web and 60 pass it through the front side of the left hand opening in the bar of the buckle as shown in the drawing at D, and the right hand strip of web through the back side of the right hand opening in the bar of the 65 buckle as shown in the drawing at E, and then bring the ends of the strips of web together and form the buttonhole or loop, in that end of the strap, by sewing together as in drawing at B, which completes and forms 70 the "suspender end" according to my invention, the whole when complete being as shown by the drawing marked D, E, A, B.

The web straps with the buttonholes or loops formed therein as above described can 75 be applied to the various kinds of suspender buckles and clasps in the same manner as to the tongue buckle as above described.

What I claim as my invention, and desire to secure by Letters Patent, is— 80

The double attachment or connection of the straps with the buckle, substantially as above described and set forth.

JULIUS HOTCHKISS.
